UNITED STATES PATENT OFFICE

CHARLES J. ZIGLER AND WILLIAM P. HOLDEN, OF CHICAGO, ILLINOIS.

ELECTRIC SWITCH.

Application filed April 18, 1921. Serial No. 460,113.

To all whom it may concern:

Be it known that we, CHARLES J. ZIGLER and WILLIAM P. HOLDEN, both citizens of the United States, residing at Chicago, in the county of Cook and State of Illinois, have invented certain new and useful Improvements in Electric Switches, of which the following is a specification.

This invention relates to electric box switches of the knife blade type and constitutes either a complete electric switch of this type or an attachment which may be applied to existing box switches for operating them with a quick throw in either direction. Among the objects of the invention are: to provide switch operating means which will produce a quick throw of a bladed switch in either direction; to provide a complete electrical switch of this kind the parts of which are readily applicable to existing switches for operating them the same way; to provide a quick throw switch which may be operated without opening the switch box; to provide improved adjustable means for automatically throwing the switch blades out of closed position if a poor contact is made and to return the handle to off position; to afford a common lock for the switch box alone or for the switch operating means in connection with the box; and in general, to produce the construction herein shown and described.

In the accompanying drawings, Fig. 1 is a side view of a switch box and the operating member of a switch of this kind; Fig. 2 is a plan view of the switch in closed position; Fig. 3 is a sectional view illustrating the locking means; Fig. 4 is a sectional view showing the switch operating means taken on the line 4-4 of Fig. 2; and Fig. 5 is a sectional view taken on the line 5-5 of Fig. 2.

This invention is illustrated as applied to a three pole switch of the knife blade type, although it has a more general application to a switch of any number of poles or of this type. The switch comprises a block 1 of insulating material suitably mounted in a protecting box 2 preferably of sheet metal having a hinged cover 3 which fits over the box.

Mounted on the insulating block 1 is an ordinary knife switch construction comprising fuse holding clips 4 and 5 and fuses 6, 55 switch blades 7 pivotally connected in an

extension on the hinge jaws 5 and engaging the outwardly bent spring tongues of co-operating jaws 8. The power and line conductors are connected to extensions of the clips 4 and 8 by terminal lugs 9.

The knife blades 7 are joined for operation together by an insulated cross head 10 connected separately to the blades by staples 11 extending through the cross head and secured in place by fastening devices 12.

One side of the box 2 is formed with a slot 13 which extends to a point above the clips 5 and the opposite side of the box is formed with a perforation 14 to receive the end of a cross rod or tumbler shaft 15. An arm 16 is disposed on the shaft 15 between each pair of blades 7. These arms are split at the ends which are slipped over the shaft 15 and the arms are held rigidly in place on the shaft 15 by rivets or pins 17. Between the arms 16 and at the ends of the shaft 15 insulating sleeves 18 of fibre or other suitable material are pressed on the shaft so that there will be no danger of electrical contact between the shaft and any of the switch parts. When one end of the shaft 15 is inserted in the perforation 14, the other end is inserted at the bottom of the slot 13, and the projecting end of the shaft 15 is formed or provided with an operating arm or handle 19 on the outside of the box which has an eye 20 at the outer end thereof. The operating shaft 15 is held in place by a strip or plate 21 fitting down over the shaft and attached by means of fastening devices 22 to the box 2 at the sides of the slot 13. This strip 21 extends through an opening 23 in the cover and has an eye 24 at the upper end adapted to receive a lock 25 for preventing the unauthorized opening of the cover 3.

Surrounding the shaft 15 at the end of the box 2 is a coil spring 26 one end of which engages the arm 19 and the other end is adjustably fastened by means of a screw 27 to one of a plurality of holes 28 to vary the tension of the spring.

The connection between the arms 16 and the switch cross head 10 consists of a right angled clip 29 extending under the cross bar and attached thereto by a fastening nut and screw 30 with the head of the screw on the top of the bar for engagement by the arms during part of their switch closing movement. The upward extension of this

clip 29 has an elongated hole 31 to receive the end of the arm 16 and to allow it to turn relatively thereto.

When the shaft 15 is operated the engagement of the extremities of the arm 16 with the clips 29 on the cross head bar 10 will operate the switch depending upon the direction of movement of the shaft 15. The extremities of the blades 7 make a spring contact with the jaws 8 and if a sufficient contact is not made with the jaws the spring 26 is operative to pull the blades out of contact with the jaws. This is for the purpose of insuring that a proper and sufficient contact is made.

The construction thus described has a quick throw action as will be more apparent from Fig. 4 for the arms 16 have both a sliding and a turning engagement with the clips 29 and the radius of the arm 16 where it engages the cross head clip 29 of blade 7 is less than the length of the blade that engages the contact jaws 8. The result of this is that the circumference or arc of movement of the arms 16 is less in length than that of the contact blades 7, and as the axis of the shaft 18 is eccentric to the pivot point of the blades 7, a differential connection is made by the arms 16 and clips 29 which produces the more rapid movement of the switch blades 7, thereby causing a quick make and break connection of the contact blades because of the turning and sliding mechanical connection between the two parts.

It is contemplated that this construction will be incorporated as a complete switch of this type, and also that the quick make and break feature may be separately applied and used in connection with knife switches of the same type already installed and in use.

From this description it will also be seen that we provide an enclosed switch construction having an operating shaft which is straight throughout its entire length within the box. This not only lessens the cost of construction but, taken with the means for connecting the same to the switch, overcomes a number of objectionable features of the prior constructions of this same general character. For instance, with switches having shafts which are bent within the box it has been found that there is a tendency for the bent arm or shaft to yield and in some instances this yielding is sufficient so that the switch blades are not opened simultaneously. It has also been more or less common to use springs in connection with the opening mechanism for giving a quick break to the switch blades. These springs have been found to jar the mechanism whenever the switch is opened and such jarring is apt to loosen the different parts or cause other injury. With our improved

construction the straight shaft is not apt to bend and furthermore the elimination of the springs avoids the difficulties incident to such constructions.

We claim:

1. A device of the character set forth comprising a casing having a knife switch mounted therein, a shaft which is straight throughout its length within the casing, pivotally mounted in said casing and means connecting the shaft with the switch blades for opening and closing the blades when the shaft is rotated.

2. A device of the character set forth, comprising a box, a knife switch mounted in said box, a shaft extending through the box and pivoted therein adjacent to the hinges of the switch blades, said shaft being straight throughout its length within the box, a handle for the shaft arranged exteriorly of the box and means connecting the shaft with the switch, whereby the switch will be opened and closed by turning the shaft.

3. In a switch construction, the combination of a box having a switch blade pivotally mounted therein, a straight shaft passing through the box adjacent to the pivot of the blade and rotatably mounted in the box, means for turning said shaft, an arm on the shaft and a clip connected with the blade, said clip having an opening for receiving the arm, the arrangement being such that the clip will slide along the arm as the arm is moved to open or close the blade.

4. A switch construction, comprising a casing, a knife switch mounted in said casing, said switch having a plurality of pivoted blades, a cross bar connecting said blades intermediate of their ends, clips on said cross bar, a straight shaft pivotally mounted in the casing adjacent to the hinges of the blades and one or more arms secured to the shaft, each of said arms engaging with a hole in a corresponding clip, whereby the switch will be opened or closed as the shaft is turned.

5. The combination with a pivoted switch blade, a resilient engaging contact, of a receptacle therefor, a shaft pivotally mounted in the receptacle, an arm projecting from said shaft, a sliding connection between the arm and the blade, and a resilient connection between the box and the operating member to throw the blade out of engagement with its contact when its contact does not sufficiently engage it.

6. The combination with a knife switch having an insulating cross head, of a switch containing receptacle, switch operating means comprising a straight shaft rotatable in the receptacle, an arm on the shaft having a differential connection with the cross head, and insulating sleeves mounted on the

shaft by slipping them on the straight portion thereon to protect it from the switch parts.

7. An operating attachment for knife switches comprising a straight shaft with an operating crank handle at one end, an arm attached to and projecting from the shaft, and means loosely engaging the free extremity of the arm adapted to be continuously and slidably connected to the bladed portion of the switch for differentially operating the switch when the shaft is turned.

8. The combination with a switch box having a hinged cover, a slot in the side of the box adjacent the free edge of the cover, of a switch operating shaft mounted in the box and insertable through the slot thereof, a plate to hold the shaft in place attachable at the sides of the slot and projecting above the edge of the box with an eye in the projecting end, the cover being formed with a perforation which slips over the projecting end of the plate, and an arm in connection with the shaft having an eye which registers with the eye of said plate to receive a common locking member.

9. The combination with a knife switch, of a box in which it is mounted, an operating attachment therefor, said attachment having a tumbler shaft with a crank end extending outside the box, an operating arm attached to the shaft, and a member insulated from the switch blade and having an elongated perforation through which the operating arm extends to form a continuous sliding differential connection therewith when the shaft is rotated.

10. A switch operating attachment for knife switches comprising a straight shaft with a crank handle at one end, an operating arm attached to and projecting from the shaft, means to form a varying differential connection between the free end of said arm and the switch, and a spring attachable to the shaft and to some fixed part for automatically operating the attachment when the knife switch does not sufficiently engage its contacts.

11. The combination with a switch and a receptacle therefor having a hinged lid, of an operating device for the switch having a crank arm outside of the box with an eye at the outer end, a plate attached to the side of and extending through the lid of the box when it is closed and having an eye which registers with the eye of the arm, means forming a connection between the operating devices and the switch, and means engaging the eyes of the plate and the crank arm for locking the lid closed and for locking the operating member in open position when the lid is open or closed.

12. The combination with a switch having pivoted blades and an insulating cross head, of an operating member therefor comprising a rotatable shaft, arms mounted on the shaft between the blades, insulating sleeves surrounding the shaft between the arms for insulating it from the switch blades, a perforated part through which each of the arms is slidable without lost motion, means for attaching said parts to the cross head, and means for rotating the shaft to operate the switch through the cross head connection.

13. A switch having a pivoted blade, of an eccentrically pivoted tumbler shaft, and means forming a positive and sliding differential turning connection between the shaft and the blade for accelerating the movement of the latter with respect to the shaft.

14. The combination with a switch box having a hinged cover with a lid in the free edge thereof and a projection extending through the slot when the cover is closed with an eye in the projecting portion, of a switch operating shaft mounted in the box having a crank arm with an eye at the end which registers with the eye of the said projection to receive a common locking member.

15. A switch construction comprising a metal enclosure with a knife switch mounted therein, a shaft pivoted in said enclosure, connections from the shaft to the switch for operating the switch and insulation on the shaft adjacent to the switch parts.
